UNITED STATES PATENT OFFICE.

MARY I. HENDERSON, OF LOS ANGELES, CALIFORNIA.

DESIGN FOR A PARASOL.

47,559.

Specification for Design.

Patented July 13, 1915.

Application filed February 8, 1915. Serial No. 6,857. Term of patent 7 years.

To all whom it may concern:

Be it known that I, MARY I. HENDERSON, a citizen of the United States, residing at Los Angeles, in the county of Los Angeles and State of California, have invented a new, original, and ornamental Design for Parasols, of which the following is a specification, reference being had to the accompanying drawing, forming part thereof.

Figure 1 is a perspective view of the parasol illustrating my new design. Fig. 2 is a side elevation of the parasol.

I claim:

The ornamental design for a parasol as shown.

MARY I. HENDERSON.

Witnesses:

MARGUERITE BATES,
MILDRED BATES.
